FLASK.

Patented Dec. 4, 1888.

UNITED STATES PATENT OFFICE.

LE ROY W. FAIRCHILD, OF NEW YORK, N. Y.

DESIGN FOR A FLASK.

SPECIFICATION forming part of Design No. 18,777, dated December 4, 1888.

Application filed November 6, 1888. Serial No. 290,168. Term of patent 3½ years.

To all whom it may concern:

Be it known that I, LE ROY W. FAIRCHILD, of New York, in the county of New York and State of New York, have invented a new Design for Flasks, of which the following is a specification.

This invention consists of a design for pocket-flasks.

The accompanying print from a wood-cut represents one side of a flask with my design thereon.

The design consists of a central field or portion having thereon two female figures represented in the attitude of dancing. These figures are surrounded by a heavy border composed of a series of scrolls of various forms, as shown in the cut. The outline formed by the edges or outer boundaries of the flask is also given an undulating or wavy form, thus rendering it still more ornamental. The figures and scroll-work are preferably struck up in high relief, so as to impart a bold and rich appearance.

What I claim is—

The design herein described and shown for flasks.

In witness whereof I hereunto set my hand in the presence of two witnesses.

LE ROY W. FAIRCHILD.
